UNITED STATES PATENT OFFICE.

ANDREW JACKSON COLVIN, CLAUDE GATCH HOCKETT, AND JOHN WILLIAM FITZPATRICK, OF GRANTS PASS, OREGON.

HANDHOLD-FORMING MACHINE.

No. 856,767.

Specification of Letters Patent.

Patented June 11, 1907.

Application filed October 12, 1906. Serial No. 338,595.

To all whom it may concern:

Be it known that we, ANDREW JACKSON COLVIN, CLAUDE GATCH HOCKETT, and JOHN WILLIAM FITZPATRICK, citizens of the 5 United States, and residents of Grants Pass, in the county of Josephine and State of Oregon, have invented a new and Improved Handhold-Forming Machine, of which the following is a full, clear, and exact description.

The invention relates to wood working machinery, and its object is to provide a new and improved hand hold forming machine more especially designed for cutting hand holds in blank boards employed for forming 15 boxes and the like.

The invention consists of novel features and parts and combinations of the same, which will be more fully described herein- 20 after and then pointed out in the claims.

A practical embodiment of the invention is represented in the accompanying drawings forming a part of this specification, in which similar characters of reference indicate cor- 25 responding parts in all the views.

Figure 1 is a plan view of the improvement, parts of the hopper containing the blanks being shown in section; Fig. 2 is a longitudinal sectional side elevation of the same on the line 2—2 of Fig. 1; Fig. 3 is a cross section of 30 the same on the line 3—3 of Fig. 1, and Fig. 4 is a cross section of part of the feed mechanism for the blanks, the section being on the line 4—4 of Fig. 1.

On a suitably constructed framework A is mounted a table B supporting a hopper C for containing a pile of blanks D, the lowermost of which is moved from under the pile one at a time by a feeding block F, to move a blank 40 along guideways E over the table B to and between dado or cutter heads G, G', for the latter to cut hand holds into opposite faces of the blank D, and which blank being afterward cut in two sections so as to provide a hand hold for each blank section. The cutter heads G and G' have their shafts G² and G³ journaled in suitable bearings carried on cross heads H and H' mounted to slide toward and from each other in vertical guide- 45 ways H² attached to the framework A, as plainly illustrated in the drawings. The cross heads H and H' are reciprocated simultaneously from a main driving shaft I extend-

ing transversely and journaled in suitable bearings held on the main frame A, and one end of the said driving shaft I is provided with a pulley I' connected by a belt I² with other machinery, for imparting a continuous rotary motion to the shaft I. On the latter are mounted eccentrics J and J' connected by 55 their eccentric rods J², J³ with the cross heads H and H', so that when the machine is in operation a continuous reciprocating motion is given to the cross heads H and H', to move the cutter heads G and G' simultaneously toward and from each other. In order to regulate the depth the cutter heads G and G' cut into the opposite faces of the blank D the eccentric rods J², J³ are provided with turn 60 buckles J⁴, J⁵ to lengthen or shorten the said eccentric rods and consequently to move the cross heads H and H' correspondingly and likewise the cutter heads G and G', for the latter to cut to a greater or less depth into the blank D. The feed block F operates in 65 unison with the reciprocating motion given to the cutter heads G and G' and for this purpose the feed block F is mounted to slide lengthwise in suitable guideways F' arranged on the main frame A, and the said feed block 70 F is pivotally connected by a pitman F² with a crank arm F³ secured on the main shaft I, so that when the latter is rotated a reciprocating motion in a lengthwise direction is given to the feed block F, and when the latter 75 moves forward in the direction of the arrow a' then it moves the lowermost blank D out from under the pile D contained in the hopper C, and on the return movement of the feed block F in a lengthwise direction the 80 block F simply raises the pile of blanks D until it has passed to a rearmost position, it being understood that for this purpose the top of the feed block F is beveled to accomplish the desired result. Now when the feed 85 block F moves forward the cutter heads G and G' move apart and out of engagement with the blank D acted on at the time, and when the feed block F is on the return stroke the cutter heads G and G' move toward each 90 other and cut into opposite faces of the blank D extending between the cutter heads G and G' at the time. In order to regulate the stroke 95 of the feed block F according to the width of the blanks D treated at the time, the connection between the pitman F² and the crank 100

arm F^3 is adjustable by a wrist pin F^4 adjustable within an elongated slot F^5 formed in the crank arm F^3 .

In order to rotate the cutter heads G , G' from the main shaft I the following arrangement is made: On the shafts G^2 , G^3 are secured pulleys K and K' connected by belts K^2 , K^3 with pulleys K^4 , K^5 secured in a countershaft K^6 journaled in suitable bearings on the rear end of the main frame A . On the countershaft K^6 is secured a pulley L connected by a belt L' with a pulley L^2 attached to the main shaft I , so that when the latter is rotated a rotary motion is given to the countershaft K^6 , which by the pulleys K^4 , K^5 , the belts K^2 , K^3 and the pulleys K , K' imparts a rotary motion to the shafts G^2 , G^3 and consequently to the cutter heads G , G' . The belt K^3 is preferably crossed to rotate the cutter head G' in the opposite direction to the cutter head G . The blank D acted on by the cutter heads G , G' at the time is held against outward movement by spring catches N secured to the guideways E , it being understood only necessary for an ordinary workman to keep the hopper filled with blanks. 85

10 The blank D acted on by the cutter heads G , G' at the time is held against outward movement by spring catches N secured to the guideways E , it being understood only necessary for an ordinary workman to keep the hopper filled with blanks. 80

15 The blank D acted on by the cutter heads G , G' at the time is held against outward movement by spring catches N secured to the guideways E , it being understood only necessary for an ordinary workman to keep the hopper filled with blanks. 75

20 The blank D acted on by the cutter heads G , G' at the time is held against outward movement by spring catches N secured to the guideways E , it being understood only necessary for an ordinary workman to keep the hopper filled with blanks. 70

25 The blank D acted on by the cutter heads G , G' at the time is held against outward movement by spring catches N secured to the guideways E , it being understood only necessary for an ordinary workman to keep the hopper filled with blanks. 65

30 The blank D acted on by the cutter heads G , G' at the time is held against outward movement by spring catches N secured to the guideways E , it being understood only necessary for an ordinary workman to keep the hopper filled with blanks. 60

35 The blank D acted on by the cutter heads, see Fig. 2. The guideways E are held transversely adjustable on the top of the table B to accommodate blanks D of different width, and for this purpose each guideway is provided with slotted lugs E' engaged by bolts E^2 held on the table B . The feed block F extends up through a slot B' formed lengthwise in the table B approximately midway between the guideways E . 55

40 The hopper C is preferably made of a number of posts C' lengthwise adjustably secured by set screws C^2 on the guideways E to move with the latter. A cross board C^3 is held vertically adjustable on the front posts C' of the hopper C by the use of bolts C^4 , and this board C^3 extends with its lower edge close to the top of the lowermost blank D , to prevent more than the lowermost blank D from being pushed out of the hopper C at a time by the feed block F . 50

45 The operation is as follows: When the several parts are in the position illustrated in the drawings and the main shaft I is rotated, then the cutter heads G , G' cut into the top and bottom faces of the blank D in position between the cutter heads G , G' at the time. As soon as the hand holds have been cut to the desired depth the cutter heads G , G' move vertically away from the blank provided with the hand holds, and at this time

the feed block F moves forward in the direction of the arrow a' , and pushes the lowermost blank D out from under the pile of blanks D and forward in the guideways E , so that the blanks D in front of this lowermost blank D are moved forward, and the outermost finished blank is moved out from between the cutter heads G , G' and another blank D is moved between the said cutter heads, and its movement is limited by the spring catches N . During the return stroke of the feed block F the cutter heads G , G' move toward each other and cut hand holds into the top and bottom faces of the blank D extending between the cutter heads G , G' at the time. 80

From the foregoing it will be seen that a large number of blanks can be provided with hand holds in a comparatively short time and without requiring skilled manual labor, it being only necessary for an ordinary workman to keep the hopper filled with blanks. 75

It will also be noticed that by each operation a blank is provided with two hand holds, and when the blank is subsequently divided into two box sections, each box section has a hand hold. By having two cutter heads G , G' cutting simultaneously into the blank at opposite faces and opposite each other no further holding down devices for the blank are required. 95

Having thus described our invention, we claim as new and desire to secure by Letters Patent:

1. A machine of the class described, comprising a hopper for containing a pile of blanks, a feed mechanism for removing the lowermost blank from under the pile to a hand hold forming device, a pair of cutter heads for cutting hand holds on the opposite faces of the said moved blank, a spring stop for temporarily restraining the movement of the blank when between the cutters, and means for imparting movement in unison to the said feed mechanism and the said cutter heads for the latter to cut the blank at the time the feed mechanism is on the return stroke and to move out of engagement with the blank at the time the feed mechanism moves another blank forward. 100

2. A machine of the class described comprising a pair of oppositely disposed revolute cutter heads, means for simultaneously moving the said cutter heads toward and from each other, means for feeding a blank between the cutters during their movement away from each other, and a spring stop against which the blank is fed. 115

3. A machine of the character described, comprising a pair of oppositely disposed cutters, means for feeding a blank between the cutters, a spring stop for temporarily restraining the forward movement of the blank, and against which the blank is fed, means for moving the cutters in unison toward the 120

blank, and means for preventing the backward movement of the blank during the operation of the cutters.

4. A machine of the class described, comprising a pair of oppositely disposed revoluble cutter heads, means for simultaneously moving the said cutter heads toward and from each other, and a feed mechanism operating in unison with the said cutter heads for feeding a blank between the cutter heads at the time the cutter heads are in extreme apart positions, the feeding mechanism being on the return stroke during the time the cutter heads move toward each other and become active.

5. A machine of the class described, provided with a pair of revoluble cutter heads, cross heads mounted to reciprocate in unison and in which the cutter heads are journaled, means for imparting a reciprocating movement to the cross heads to move the cutter heads simultaneously toward and from each other, means for moving a blank between the cutter heads during their movement from each other, and a spring stop against which the blank is fed for temporarily restraining the movement of the blank.

6. A machine of the class described provided with a pair of revoluble cutter heads, cross heads mounted to reciprocate in unison and in which the cutter heads are journaled, eccentrics having adjustable eccentric rods connected with the said cross heads, a main

shaft carrying the eccentrics, a hopper for containing a pile of blanks, a feed mechanism actuated from the said main shaft for removing the lowermost blank from the said hopper and moving it between the said cutter heads at the time they are in widest separate position and a spring stop against which the blank is fed for temporarily restraining the forward movement thereof.

7. A machine of the class described provided with a pair of revoluble cutter heads, cross heads mounted to reciprocate in unison and in which the cutter heads are journaled, eccentrics having adjustable eccentric rods connected with the said cross heads, a main shaft carrying the eccentrics, a hopper for containing a pile of blanks, a reciprocating feed block for moving the lowermost blank out of the said hopper, a crank arm on the said main shaft, a link connecting the said crank arm with the said feed block and a spring stop against which the blank is fed for temporarily restraining the forward movement thereof.

In testimony whereof I have signed my name to this specification in the presence of two subscribing witnesses.
